US0D1018901S

(12) **United States Design Patent** (10) **Patent No.:** **US D1,018,901 S**
(45) **Date of Patent:** **** Mar. 19, 2024**

(54) **BLOCK FOR CONSTRUCTION**

(71) Applicant: **OSBLOCK INC.**, Sainte-Monique (CA)

(72) Inventor: **Marco Tremblay**, Sainte-Monique (CA)

(73) Assignee: **Osblock Inc.**, Sainte-Monique (CA)

(**) Term: **15 Years**

(21) Appl. No.: **35/515,342**

(22) Filed: **Apr. 13, 2022**

(80) **Hague Agreement Data**

Int. Filing Date: **Apr. 13, 2022**

Int. Reg. No.: **DM/222318**

Int. Reg. Date: **Apr. 13, 2022**

Int. Reg. Pub. Date: **Oct. 14, 2022**

(51) **LOC (14) Cl. 25-01**

(52) **U.S. Cl.**

USPC **D25/113**

(58) **Field of Classification Search**

USPC D25/102, 112-118, 138, 151, 163

(57) **CLAIM**

The ornamental design for a block for construction, as shown and described.

DESCRIPTION

Figure 3.1 is a top perspective view of a block for construction;

Figure 3.2 is a bottom perspective view of the block for construction of Figure 3.1;

Figure 3.3 is a front elevational view of the block for construction of Figure 3.1;

Figure 3.4 is a rear elevational view of the block for construction of Figure 3.1;

Figure 3.5 is a top plan view of the block for construction of Figure 3.1;

Figure 3.6 is a bottom plan view of the block for construction of Figure 3.1;

Figure 3.7 is a right-side elevational view, enlarged, of the block for construction of Figure 3.1; and

Figure 3.8 is a left-side elevational view, enlarged, of the block for construction of Figure 3.1.

The broken lines in the drawings depict portions of the block for construction that form no part of the claimed design. The drawings contain a symbolic break and the portion between the break lines forms no part of the claimed design.

1 Claim, 5 Drawing Sheets
